J. Comstock,

Power Hammer,

N° 12,770.

Patented Apr. 24, 1855.

John Comstock

UNITED STATES PATENT OFFICE.

JOHN COMSTOCK, OF NEW LONDON, CONNECTICUT, ASSIGNOR TO PETER NAYLOR.

FORGE-HAMMER.

Specification of Letters Patent No. 12,770, dated April 24, 1855.

To all whom it may concern:

Be it known that I, JOHN COMSTOCK, of the city and county of New London and State of Connecticut, have invented and 5 made certain new and useful Improvements in Forging-Hammers; and I do hereby declare that the following is a full, clear, and exact description of the construction and operation of the same, reference being had 10 to the annexed drawing, making part of this specification, wherein—

Figure 1, is a plan, Fig. 2, is a side elevation, Fig. 3, is an elevation at the end A, and Fig. 4, is an elevation at the end B, collectively showing my improved forging hammer as ready for use.

The like marks of reference denote the same parts.

The nature of my said invention consists 20 in so applying a loose belt with cams and other parts, that a forging hammer can be brought to strike heavy or light blows to finish work, or the hammer be entirely stopped, although the power which drives 25 the parts continues its motion; thus placing the attendant in possession of facilities for causing the power to strike the blow desired, through the intervention of simple mechanical means.

30 *a*, is a pulley on a shaft 1, supported in suitable bearings, to which a continuous rotation is given by competent power; a loose belt 2, passes from the pulley *a*, around a pulley *b*, on a shaft *c*, set in bearings 3, 3; 35 and near the end of this shaft *c*, a fly wheel *d*, is attached so as to cause a steady rotation of the shaft *c*.

40 *e*, is a pulley hung on a frame 4, moving on centers 5, which when brought against the belt 2, tightens the same on its pulleys; this tightener is drawn back from the belt by a spring 6, when not acted on by a rod *f*, to a right angle lever *g*, on a fulcrum 7, to the end 8, of which lever *g*, the foot of the 45 operator is applied to tighten the belt 2, and cause the shaft *c* to be rotated.

When it is desired to stop the revolutions of the shaft *c*, the operator removes his foot from the end 8 of the lever, and allows the 50 spring 6 to draw back the tightening pulley, and I cause the same movement to apply a brake to the fly wheel, by means of a pin 9, on the side of the frame 4, taking a slot in a bent lever *h*, on a fulcrum 10, the other 55 end of which acts on a lever *k*, lying nearly horizontal, to the opposite end of which a

break block 11, is attached as shown in Fig. 3, thus the revolutions of the shaft *c*, are entirely under the control of the operator for when but a light pressure is given to the tightening pulley the belt 2 will partially slip; thus the speed can be regulated or the shaft *c*, stopped.

C, is the bed of the forging hammer supported on suitable foundations D.

m, is the forging block or die, which may be made adjustable as usual, so as to coincide with the die on the hammer if required; at the other end of the bed short standards *n*, are fitted to receive a frame *o*, attached 70 to the standards by bolts 16 passing through slots in the standards into a plate 17,—by this means the frame *o*, and hammer can be raised or lowered as desired.

18, 19, are center screws passing through 75 the frame *o*, into the ends of the hammer trunnions *p*, to which the slings or handle *q* of the hammer *r*, are attached and *s*, is the movable face or die of the hammer.

v, is a cross piece between the slings *q*, to 80 which a bar 22, and screw shackle are attached connecting the same to a spring pole or any similar means for lifting the hammer to the required height; the screw shackle affording a means for so doing, with great 85 accuracy.

t is a cross bar over the slings *q*, attached to them in any suitable manner so that it can be moved if desired nearer to, or farther from the trunnions *p*, so as to vary the lever- 90 age on the hammer. To this cross bar *t*, a rod 19 is connected that passes down to the screw shackle 20, which connects to the horizontal lever *u*, (see Fig. 3) that is jointed at 21, by a fulcrum on the foundation D, and 95 the other end passes across beneath the shaft *c*.

On the shaft *c*, over the lever *u*, cams *i*, and *i'*, are fitted either to slide on a square part of the shaft or on a key, and 12, is a 100 fork passing into a neck between said cams; this fork is on the end of a rod *l*, running to a bent lever 13, the horizontal arm of which terminates as a stud 15, passing through a hole in the foot piece 8. 105

14 is a contractile spring which unless otherwise acted on keeps the longest cam *i* over the lever *u*.

It will now be apparent that the operation of these parts is, that when the attendant presses down the end 8 of the lever *g* the hammer is moved with a speed propor-

tioned to the tightness of the belt 2.—the cam i , by its length giving a heavy blow; the force of which blow can be regulated by the screw shackle 20, and the spring w , lifts 5 the hammer again each blow; and when the forging is nearly complete or requires but slight blows the workman presses down the end 15 of the lever 13, which slides the cams i and i' , along on the shaft c , bringing the 10 cam i' , into operation, which being shorter does not strike so hard a blow but one suited for finishing the forging.

I do not claim a tightening pulley in itself as this is well known, but I am not aware 15 that a tightening pulley and break have ever before been used as herein set forth, by which the speed of the blow is regulated by the tightness of the belt or the same is stopped entirely by the break, while the 20 motive power still propels the belt. And I am well aware that a hammer has been so set as to be drawn down to give the blow and then raised again by a spring, therefore I do not claim the same in itself, and I am 25 also well aware that different sized cams have been used for raising a forging hammer therefore I do not claim the different 30 lengths of cams in themselves, but I am not aware that two or more cams of varying lengths have ever before been combined with

a lever and adjustable screw shackle to pull down a hammer and give the blow, whereby I am enabled to use a definite amount of motion given by a cam, to forge articles of various sizes, the screw shackle 35 giving the facility for regulating the point to which the hammer is pulled.

Therefore what I desire to secure by Letters Patent is—

1. I claim the method herein described 40 and shown for regulating the speed of the blows given by a forging hammer, by the use of a tightening pulley combined with the break applied to the fly wheel substantially as specified.

2. I claim the method herein described 45 and shown of regulating the amount which a hammer is drawn down to give the blow by rotating cams, by combining with said cams and hammer the adjustable screw shackle 20, and lever u , the whole constructed and combined substantially as specified.

In witness whereof I have hereunto set my signature this twenty-eighth day of February, 1855.

JOHN COMSTOCK.
